SEAT SUPPORT

Walter J. Kiefer, Belvidere, Ill.

Application October 11, 1943, Serial No. 505,775

5 Claims. (Cl. 155—95)

1

This invention relates to seat supports and has special reference to a seat support having a novel form of return mechanism for returning a revolving chair or seat to a preselected position when vacated by the occupant.

The primary object of the invention is the provision of a seat support having a chair return mechanism which is cheaper to make than prior art types, which is simpler in form, and which operates smoothly and without noise.

The object is also to produce a construction which is positive in operation as distinguished from those in which the force of gravity is relied upon for returning the chair.

Other objects and advantages will appear from the following description and the accompanying drawing, in which—

Figures 1 and 2 are side elevations and top views, respectively, showing seat returns of the character contemplated by this invention;

Fig. 3 is a top view of the chair return mechanism viewed from a plane directly under the seat of the chair;

Fig. 4 is a fragmentary view similar to Fig. 3, partly in section, showing the parts in position when the chair is rotated toward the end of its movement in one direction;

Fig. 5 is a section on the line 5—5 of Fig. 2, and

Fig. 6 is a side elevation of the seat return mechanism.

While the seat support is of general utility, Figs. 1 and 2 are shown for the purpose of illustrating one advantageous use in which the numeral 1 designates a restaurant counter or bar having a series of chairs arranged therein in spaced relation as shown in Fig. 2, the chairs being rotatably supported on pedestals 8 usually secured in the floor. As is well recognized in the art, this chair arrangement presents some problem in maintaining an orderly arrangement of the chairs, and for this purpose it is common practice to provide seat return mechanism arranged to rotate the chair or seat to a preselected position. Thus, as the occupant leaves the chair it is rotated to a position such as that shown at 9 in Fig. 2, and it is desirable that as soon as the occupant releases the chair it should be returned to the position shown at 11 with the seat portion 12 disposed adjacent the counter and the back portion 13 spaced therefrom. The present invention is directed to a mechanism adapted to automatically return the chair to the position shown at 11 and to permit the chair to be rotated to a position approaching that shown at 9 to permit the occupant to vacate the chair with a minimum of inconvenience.

2

In the present embodiment of the invention the chair is carried upon the pedestal 8, the pedestal being secured in the floor and having a central bore 14. Attached to the bottom of the chair seat 12 is a spider having, in this instance, three arms 15, 16 and 17 attached to the seat by means of screws as indicated at 18, the spider having a spindle 19 depending therefrom. The spindle has a larger portion 21 adjacent the bottom of the seat terminating in a spindle 22 of smaller diameter adapted to be received in the bore 14 of the pedestal, a shoulder 23 being disposed between the two portions of the spindle adapted to rest on an anti-friction bearing 24 disposed in a counterbore 25 at the upper end of the pedestal. The portion 21 of the spindle has gear teeth disposed annularly thereof as indicated at 26, these teeth forming the pinion of a rack and pinion assembly, as will presently become apparent.

Attached to the pedestal adjacent the upper end thereof is a bracket 27 secured in position by means of cap screws 28, the bracket having a cylindrical opening for the passage of a rod 29, the rod being secured therein against movement by a set screw 31. The bracket also has a rectangular slot 32 disposed opposite the pinion 26, this slot serving as a support and guide for a rack bar 33 having a plurality of teeth 34 disposed therealong and arranged to engage the teeth of the pinion 26. The bracket 27 supports the bar from below and also assists in retaining the bar to prevent it from being forced out of engagement with the pinion. The ends of the rack bar 33 have flanges 35 and 36 disposed substantially at right angles to the main expanse of the bar, the flanges having openings 37 and 38 for the free reception of the rod 29 (note Fig. 4). Disposed between the bracket 27 and the flanges 35 and 36 are coiled springs 39 and 41 coiled about the rod 29, these springs being of the same length and substantially the same properties so that when the pinion 26 occupies a central location on the rack bar 33 as shown in Figs. 3 and 6, the springs will be compressed to substantially the same extent.

The previously described mechanism is attached to the bottom of the chair seat in such manner that the central portion of the rack 33 engages the gear when the seat faces the counter in the manner shown at 11 in Fig. 2 and the springs 39 and 41 are then equally stressed. It will be seen that when the seat is rotated about the spindle 22 to the position shown at 9 in response to evacuation of the chair by an occupant, the pinion 26 is rotated, moving the rack toward one end in the manner shown in Fig. 4, thereby

compressing the spring 39. When the chair is released the spring 39, bearing against the flange 35, forces the rack back to its normal position, the rack driving the spindle and the chair in response to this movement, thereby returning the chair to the normal position as shown in Figs. 3 and 6. Likewise, if the chair is rotated in a clockwise direction facing Fig. 2, the pinion 26 drives the rack in the opposite direction compressing the spring 41 which, upon release of the chair, acts to drive the rack and pinion to return the chair to its normal unoccupied position. It will be seen that this mechanism positively drives the chair back to the normal position in response to the operation of a conventional coiled spring, and the drive mechanism is a positive gear drive engaged at all times. Another advantage of this construction is that the spindle rotates on a horizontal bearing and therefore, a ball bearing such as shown at 24, may be employed to facilitate the ease of rotation. Furthermore, the elevation of the seat does not change during the rotation, and for this reason the chair is more easily rotated by the occupant in the act of vacating the chair.

I claim:

1. The combination in a chair-return mechanism for chairs of the type having a stationary support and a chair seat rotatable thereon, of a spindle arranged for attachment to the bottom of a chair seat to depend therefrom shaped for reception in said stationary support for rotation on a vertical axis about a fixed center, a pinion on said spindle rotatable therewith and with said chair seat, gear means disposed between said pinion and said support driven by said pinion, spring means disposed between said gear means and the stationary support stressed by movement of said gear means in response to rotation of said chair seat in one direction out of a preselected position and driving said pinion from said gear means upon release of said chair seat to return said chair seat to said preselected position.

2. The combination in a chair-return mechanism for chairs of the type having a stationary support and a chair seat rotatable thereon, of a spindle arranged for attachment to the bottom of said chair seat to depend therefrom shaped for reception in said stationary support for rotation on a fixed vertical axis, a pinion on said spindle rotatable therewith and with said chair seat, a rack driven in translatory movement by said pinion upon rotation of said seat, means for supporting said rack on the stationary support, and a spring acting between said rack and said stationary support positioned to be stressed upon translatory movement of the rack in response to rotation of the chair seat out of a preselected position and to drive said rack and return said chair seat to said position upon release of the latter.

3. The combination in a chair-return mechanism for chairs of the type having a stationary support and a chair seat rotatable thereon, of a

spindle arranged for attachment to the bottom of said chair seat to depend therefrom shaped for reception in said stationary support for rotation on a vertical axis, a pinion on said spindle rotatable therewith and with said chair seat, a rack engaging said pinion and driven thereby in either of two opposed directions upon rotation of said seat in opposite directions, said rack having spaced abutments, and springs between said abutments and said stationary support to normally maintain said chair seat in a preselected position, positioned to be selectively stressed upon movement of said rack in said opposite directions by rotation of said seat out of said preselected position and to drive said rack and said pinion to return said chair seat to said position upon release thereof.

4. The combination in a chair-return mechanism for chairs of the type having a stationary support and a chair seat rotatable thereon, of a spindle arranged for attachment to the bottom of said chair seat to depend therefrom shaped for reception in said stationary support for rotation on a vertical axis, a pinion on said spindle rotatable therewith and with said chair seat, a rack engaging said pinion and driven thereby in either of two opposed directions upon rotation of said seat in opposite directions, said rack having spaced abutments, and springs between said abutments and said stationary support to normally maintain said chair seat in a preselected position, positioned to be selectively stressed upon movement of said rack in said opposite directions by rotation of said seat out of said preselected position and to drive said rack and said pinion to return said chair seat to said position upon release thereof, and guide means on said support for supporting and guiding said rack.

5. The combination in a chair-return mechanism for chairs of the type having a stationary support and a chair seat rotatable thereon, of a spindle arranged for attachment to the bottom of said chair seat to depend therefrom shaped for reception in said stationary support for rotation on a vertical axis, a pinion on said spindle rotatable therewith and with said chair seat, a rack engaging said pinion and driven thereby in either of two opposed directions upon rotation of said seat in opposite directions, said rack having spaced abutments, a guide rod on said stationary support passing through said abutments to support said rack, coiled compression springs on said guide rod acting between said abutments and said stationary support to normally maintain said chair seat in a preselected position, positioned to be selectively stressed upon movement of said rack in said opposite directions by rotation of said seat out of said preselected position and to drive said rack and said pinion to return said chair seat to said position upon release thereof.

WALTER J. KIEFER.
